Fig. 2.

Fig. 3.

FIG. 1 is a perspective view of a wrapping machine showing my new design;

FIG. 2 is a left side elevation thereof;

FIG. 3 is a plan view thereof.

Portions of the machine are stippled to indicate color contrast with non-stippled portions, the variation in the density of the stippling representing different colors or shades of color. The right side of the machine corresponds substantially to the left side thereof, except for the handles. The rear of the machine is substantially

plain, except for access openings. The top elements shown in broken lines in FIG. 1 have been omitted from FIGS. 2 and 3 for convenience of illustration only. The dominant features of the design are shown in full lines.

I claim:

The ornamental design for a wrapping machine, as shown and described.
